Primary Examiner — Catherine A Tuttle(74) *Attorney, Agent, or Firm* — Law Offices of Steven W. Weinrieb(57) **CLAIM**

The ornamental design for a toy, as shown and described.

DESCRIPTION

FIG. 1 is a front, right side, top perspective view of the toy showing my new design;

FIG. 2 is a rear, right side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right side, top perspective view thereof showing the base portion of the design together with broken line elements illustrative of one intended use; and,

FIG. 10 is a right, front and bottom perspective view showing the base portion of the design together with broken line elements illustrative of an alternative use.

The broken lines depicting elements being used in association with the toy form no part of the claimed design.

1 Claim, 10 Drawing Sheets---
